UNITED STATES PATENT OFFICE.

ALBERT H. HARSHBARGER, OF BEMENT, ILLINOIS.

WAGON-STANDARD.

No. 891,215.

Specification of Letters Patent.

Patented June 16, 1908.

Application filed October 16, 1907. Serial No. 397,735.

To all whom it may concern:

Be it known that I, ALBERT H. HARSHBARGER, a citizen of the United States, and resident of Bement, in the county of Piatt and State of Illinois, have invented certain new and useful Improvements in Wagon-Standards; and my preferred manner of carrying out the invention is set forth in the following full, clear, and exact description, terminating with claims particularly specifying the novelty.

This invention relates to carriages and wagons, and more especially to the standards mounted on wagon bolsters for the purpose 15 of holding in place the wagon box or other load; and its object is to improve the construction of said standard.

To this end the invention consists in an improvement on U. S. Patent 832008 issued 20 September 25, 1906, to William W. Bruce. In said patent the base plate of the standard was bolted at its outer end to the bolster and had at its inner end a T-shaped recess which received the shank and head of a second bolt 25 mounted in and rising from the bolster. Said recess was open through the inner wall of the bolster and hence likely to become clogged, and the present improvement consists of presenting the mouth of this recess in 30 the other direction so that the inner wall of the bolster can be closed and will not become clogged.

The invention is exemplified in the structure hereinafter described and claimed, and 35 is shown in the accompanying drawings forming part of this specification and in which—

Figure 1 is a perspective view of this standard complete as mounted on a bolster; Fig. 2 40 is a central vertical section through the bolster and its bolts, and through the lower portion of the standard; and Fig. 3 is an enlarged perspective view looking into the lower end of the standard.

45 Referring to the drawings, the body of the standard is shown as composed of a vertical plate 1 intended to stand flat against the side of the wagon body, and a strengthening rib 2 preferably cast integral therewith and 50 at right angles thereto so that in cross section the body of the standard will be T-shaped. By preference rings 140 are pivotally attached to the rib, and they are adapted

to hold a stake for the purpose of lengthening the standard as usual. At its base the 55 standard is enlarged laterally into a housing 14 which has ears 9 depending from its edges and passing over the sides of the bolster 15 so as to receive the horizontal bolt 10 as shown; and said housing also has a base 60 plate 3 which is elongated beyond the rib 2 and perforated to receive an upright bolt 12 passing through it and the bolster 15. Thus far the construction is much like the patent 65 above referred to.

Coming now more particularly to the present invention, the housing is cast hollow as best seen in Fig. 3, and within it and extending outward at right angles to the plate 1 is a lug 5 having a notch 4.

The numeral 8 designates a bolt or screw seated vertically in the bolster 15 and having its head 7 above the upper face thereof, its size being such that its shank may pass into the notch 4 of the lug 5 and its head 7 be received above the latter and entirely concealed within the housing.

With the parts properly shaped and proportioned, the standard is secured to the bolster by the horizontal bolt 10 and the vertical 80 bolt 12 whose nuts are set up tight, and also by the upright bolt 8 whose head engages the lug 5. When it is desired to remove the standard, as for substitution or repair, the bolts 10 and 12 are withdrawn and the standard is moved bodily inward upon the bolster so that the notch 4 in lug 5 will slip off of the bolt 8 from beneath its head, after which the entire standard can be lifted from position. Thus it will be seen that I accomplish all that 90 was effected by the construction in the patent above referred to, and more, because the opening for the upright bolt is not exposed and the cavity within the housing is closed by the bolster so that dirt and moisture cannot 95 accumulate therein. By preference all parts are of cast iron excepting the bolts and rings, and the sizes, shapes and proportions of parts are immaterial.

What is claimed as new is:

A wagon-standard comprising a body including a vertical plate, and a hollow housing at the lower end of the body having depending ears at its edges, a base plate extending outward, and an integral lug within its hollow portion extending away from said up- 105

right plate and toward the base plate and
notched; combined with a bolster upon
which the standard fits, a horizontal bolt
through the bolster and ears, a vertical bolt
5 through the bolster and base plate, and a
headed upright member seated in the bolster
and engaged by the notch of said lug.

In testimony whereof I sign my name in
the presence of two subscribing witnesses,
this the 12th day of October, 1907.

ALBERT H. HARSHBARGER.
